UNITED STATES PATENT OFFICE.

BENJAMIN R. JOLLY, OF RALEIGH, NORTH CAROLINA.

BRACELET.

1,184,534.

Specification of Letters Patent.

Patented May 23, 1916.

Application filed December 7, 1915. Serial No. 65,523.

To all whom it may concern:

Be it known that I, BENJAMIN R. JOLLY, a citizen of the United States, and a resident of Raleigh, in the county of Wake and State 5 of North Carolina, have invented a new and Improved Bracelet, of which the following is a full, clear, and exact description.

This invention relates to bracelets and has for an object the provision of an improved 10 construction whereby the links may be arranged as a bracelet or as a necklace.

Another object in view is to provide an improved construction of a link which incloses a spring in such a manner that a flat serpentine cut spring may be used or a substantially 15 flat coiled spring may be used.

A still further object in view is to provide a link formed with a body and a sliding member together with a spring and associated parts whereby a plurality of the links may be connected together by interlocking certain sections thereof in order to produce a bracelet or necklace of any desired length.

A still further object in view is to provide 25 an improved catch conforming in appearance to the general outline of the link associated therewith so as to produce a harmonious structure when used in connection with the link.

30 In the accompanying drawings: Figure 1 is a plan view of a bracelet embodying the invention; Fig. 2 is a rear view on an enlarged scale of part of the bracelet shown in Fig. 1, the same showing in dotted lines the arrangement of the springs; Fig. 3 is a longitudinal sectional view through Fig. 2 on line 3—3; Fig. 4 is a view similar to Fig. 3 but showing the parts separated; Fig. 5 is a view similar to Fig. 4 except that one of 35 the links has been turned preparatory to removal; Fig. 6 is a transverse sectional view through Fig. 2 on line 6—6; Fig. 7 is a sectional view through Fig. 5 on line 7—7; Fig. 8 is a sectional view through Fig. 2 on line 8—8; Fig. 9 is a plan view of part of a bracelet shown connected up with a wrist watch; Fig. 10 is a rear view of part of a link and a catch embodying certain features 40 of the invention; Fig. 11 is a view similar to Fig. 10 except that the parts as shown in a different position; Fig. 12 is a section through Fig. 11 on line 12—12; Fig. 13 is a transverse section through Fig. 10 on line 13—13.

45 Referring to the accompanying drawings by numerals, 1 indicates a link which is pro-

vided with a body 2 and a slide 3, the slide of one link being connected with the body of the next adjacent link so as to form a complete bracelet, as shown in Fig. 1. If 60 desired, links 1 can be connected together and provided with catches 4, as shown in Fig. 9, so that a wrist watch may be connected to any suitable number of links. It is also evident that a large number of links 65 may be connected together so as to act as a necklace. The various links are identical in construction so that the showing of one full link and parts of other links as detailed in Figs. 2 to 8 will illustrate the invention 70 except for the catches shown in detail in Figs. 10 to 13.

75 It will be observed that each body 2 is provided with a face 5 having upstanding walls 6 and 7 which are turned over for providing runways 8 and 9. The ends of the face 5 are bent over for forming stops 10 and 11, stop 11 being adapted to engage one end of spring 12 while stop 10 limits the movement of the locking lug 13. The 80 locking lug 13 is provided with a bottom 14 and an end 15 which merges into sides 16 guided by the runways 8 and 9. The bottom 14 has a bent-up portion 17 formed with a slot 18 whereby a pintle 19 is formed 85 for turned-over end 20 of link 3, as shown more particularly in Fig. 3. By this construction and arrangement the locking lug 13 forms a jointed continuation of links 1 and is adapted to be applied and removed 90 whenever desired so as to add or take away one of the links. In order to accomplish this the runway 9 is cut away at 21 (Figs. 4 and 7) whereby when the parts are moved to the position shown in Fig. 5 the locking 95 lug can be tilted to one side and moved out of the body 2. The end of the slide 3 opposite that carrying the locking lug 13 is supplied with a bent-up stop 22 which engages spring 12 and thereby causes the 100 spring to act against the slide 3 and body 2 for normally holding the parts in the position shown in Fig. 3.

105 As the body 2 and slide 3 are broader than they are deep the spring 12 is flattened to an appreciable extent, as indicated particularly in Fig. 6. The spring may be a flat cut spring, as shown in my co-pending application Serial No. 49,723, filed September 9, 1915, or may be a coiled spring 110 widened to an appreciable extent so as to fit in between slide 3 and body 2.

The idea of broadly claiming a link which incloses a chain is not claimed in the present application, as such structure is claimed in my prior application above mentioned, the present application being an improvement over said application in certain parts which will be pointed out in detail in the appended claims.

In forming the slide 3 the edges thereof are pressed so as to provide guiding runways 23 and 24 engaging the runways 8 and 9 whereby the parts are stiffened and properly braced while properly slidingly fitted together. In forming the stops 11 it is evident that the openings 25 and 26 are provided for accommodating the guiding runways 23 and 24 as the same move back and forth. It will be observed that there are no rivets, bolts or other loose parts used in holding the slide and body together or, in fact, in holding any of the parts in proper position. The arrangement of the interlocking slide members and the stops on said members provide means for properly holding the spring in place without any auxiliary retaining members, and by arranging the notch or opening 21 and the lug 16 proper means are presented for connecting as many links together as may be desired.

Instead of connecting a number of links together as shown in Fig. 1 catches may be connected to a certain number of links if desired, as shown in Figs. 9 to 13, inclusive. This catch is provided with a body 2' similar to body 2 and a slide 3' similar to slide 3 except that it is provided with a hook 27 as shown in Fig. 12 and a lug 28 extending approximately half way across body 2'. Instead of using a spring similar to spring 12 a plate formed with a body 29 is provided, said body having extending therefrom a fairly small section or arm 30, said arm merging into projections 31 and 32. Projection 32 extends through a suitable opening in the side of body 2' so as to be operated manually and moved from the position shown in Fig. 10 to the position shown in Fig. 11. Normally the parts are in the position shown in Figs. 9 and 10 but if it is desired to remove the catch 4 from, for instance, the watch 33, lug 32 is pressed which moves the lug 31 away from the stop 28. The slide 3' is then moved outwardly to the position shown in Fig. 11 and then lug 32 may be released. Stop 28 when in this position acts as means for preventing the outward movement of lug 32. When the slide 3' is pressed back to its normal position shown in Fig. 10 lug 31 will automatically move upwardly to the position shown in Fig. 10 under the action of the spring arm 30. It will be observed that the turned-down end 10 of body 2' prevents the accidental removal of the plate 29. This plate together with the parts associated

therewith forms catch 4, which catch is connected to any of the links 1 in a similar manner to the way the links are connected together so that no additional description is thought necessary.

What I claim is:

1. In a device of the character described, a link provided with a body having upstanding walls bent over for forming guideways, said body having the ends bent over for forming stops, one of said guideways having a notch therein, a slide provided with a pivotally mounted section adapted to be forced through said notch, and a spring acting on said body and said slide for resiliently holding the slide in a given relative position.

2. In a device of the character described, a link provided with a body substantially U-shaped in cross section, said body also being formed with turned-up ends, a slide formed with guiding members engaging part of said body so as to connect the slide with the body and produce an inclosed chamber, said slide having a bent-up end acting as a stop, and a spring arranged between the body and the slide and acting on the stop on the slide and one of the ends of said body, said spring being entirely inclosed.

3. In a device of the character described, a link provided with a body having upstanding sides bent over for producing runways, one of said runways having a notch arranged therein, said body having the ends bent down for forming stops, a slide engaging said runways, said slide being provided with a stop at one end and a pivotally mounted locking lug at the opposite end, said locking lug being adapted to be forced through said notch into said body, so as to anchor the slide in the body, and a spring arranged between the stop on said slide and one of the bent down ends of the body for resiliently holding the parts in a given position.

4. In a bracelet of the character described, a plurality of links provided with a pair of plates, one of said plates being formed with turned-up portions for providing runways and also provided with a turned-up stop, and the other of said plates fitting in said runways and provided with a stop, and a flattened coiled spring arranged between said plates and engaging said stops for resiliently holding said plates in a predetermined position.

5. In a bracelet of the character described, a plurality of links, each of said links being provided with a body having up-standing bent-over sides producing runways and bent over ends for producing stops, a sliding plate formed in two parts pivotally connected together, each of said parts being provided with guiding members

fitting said runways, said sliding plates having a turned-up end producing a stop, and a spring arranged between said last mentioned stop and one of the stops on said 5 body for resiliently holding the sliding plate in a predetermined relationship with the body.

6. In a bracelet of the character described, a plurality of links and a catch for 10 connecting the links to an object, said catch comprising a body, a plate arranged in said body formed with a resilient arm having a projection extending through the body for forming a stop, and a sliding plate provided 15 with a hook member formed with a turned-down portion for interlocking with said stop and said projection.

7. In a bracelet of the character described, a plurality of links and a catch connecting the links with an article, said catch comprising a body having turned-over guideways and a pair of turned-over end members, one of said end members engaging 25 a link for connecting the catch with the link, a plate arranged in said body engaging the other of said end members, said plate being formed with a resilient arm and a projection extending from said arm near the end thereof, said projection extending 30 through an aperture of said body whereby said arm may be moved manually, and a sliding plate provided with an engaging member at one end and a turned-up stop at the opposite end, said stop extending 35 only part of the way across the body whereby when said projection is pressed manually the resilient arm is moved out of the way for permitting a forward movement of the sliding plate, said resilient arm

being adapted to move automatically in front of said turned-down stop when the sliding plate is moved back to its normal position, thus locking the sliding plate against further movement.

8. In a bracelet of the character described, a plurality of links, a catch for connecting the links to an article, said catch comprising a body, a sliding plate and a plate having a spring arm, said body being formed with turned-over members for providing runways and turned-over ends for providing stops, said body being formed with an aperture in one side thereof, said spring plate being provided with a resilient arm having a projection extending through said aperture and a second projection acting as a lock, said sliding plate being provided with means for connecting the same to an article and with a turned-down section at the opposite end, said turned-down section extending for only part of the way across said body whereby said second projection may act against the turned-down section and hold the sliding plate against movement while the resilient arm is in one position and to be moved to one side by manually pressing against the first mentioned projection so as to allow a forward movement of the sliding plate until said turned-down section strikes the first mentioned projection.

In testimony whereof I have signed my name to this specification in the presence of two subscribing witnesses.

BENJAMIN R. JOLLY.
